UNITED STATES PATENT OFFICE

106,364

DESIGN FOR A COAT

Samuel Zimmerman, New York, N. Y.

Application July 24, 1937, Serial No. 70,616

Term of patent 3½ years

To all whom it may concern:

Be it known that I, Samuel Zimmerman, a citizen of the United States of America, residing in Manhattan, county of New York, and State of New York, have invented a new, original, and ornamental Design for a Coat, of which the following is a specification, reference being had to the accompanying drawing, forming part hereof, wherein,

The circular arrangement of stitchings, as shown in Figure 1, appear solely on the inner portion of the collar.

The diagonal lines on the rear sleeve portions of the coat represent folds.

I claim:

The ornamental design for a coat, substantially as shown and described.

SAMUEL ZIMMERMAN.
